UNITED STATES PATENT OFFICE.

JAMES C. DAWLEY, OF DAYTON, OHIO, ASSIGNOR TO THE JOYCE-CRIDLAND COMPANY, OF DAYTON, OHIO, A CORPORATION OF OHIO.

LIFTING JACK.

Application filed August 5, 1925. Serial No. 48,230.

This invention relates to lifting jacks and more particularly to what is known as a self-lowering jack, in which the load moves downwardly under its own weight and its 5 downward movement is controlled by a friction brake.

The main object of the invention is to provide improved means for controlling the lowering of the load, and to this end a further object is to provide means for locking the friction devices in operative position so 10 as to positively hold the load against downward movement.

A further object of the invention is to provide an improved one-way clutch for connecting the lifting element with the brake.

A further object of the invention is to provide improved means for mounting the arms which actuate the friction members.

20 Other objects of the invention will appear as the device is described in detail.

In the accompanying drawings Fig. 1 is a front elevation, partly in section, of a lifting jack embodying my invention; Fig. 2 25 is a section taken on the line 2—2 of Fig. 1; Fig. 3 is a side elevation of the clutch, partly in section; Fig. 4 is a vertical section taken through the clutch of Fig. 3; Fig. 5 is an elevation of the supplemental housing 30 with the cover plate removed to show the actuating device and lock for the friction members in elevation; and Fig. 6 is a sectional view showing the actuating device and lock of Fig. 5 in plan.

35 In these drawings I have illustrated one embodiment of the invention and have shown the same as applied to a lifting jack of a type shown in Patent No. 1,344,117, granted June 22, 1920 to Ripsch, Dawley and Derby, 40 but it will be understood that this particular type of jack has been chosen for the purpose of illustration only, that the controlling mechanism may be applied to jacks of various kinds and may take various forms without departing from the spirit of the invention.

45 The jack as here shown comprises a base 1 having a hollow standard 2 extending upwardly therefrom and provided at its upper end with a nut 3 in which is threaded a screw 4 constituting the lifting element of the jack. Rigidly secured to the screw above the nut is a beveled gear 5 on which is supported the load engaging cap 6, a ball bear-

55 ing 7 being preferably interposed between the cap and the gear. Rigidly secured to and depending from the load engaging cap 6 is a housing 8 which embraces the standard 2 and constitutes a guide for the lifting element. Rigidly secured to one side of the 60 housing 8 near the top thereof is a supplemental housing 10 divided by a partition 11 into two compartments. Journaled in suitable bearings formed in the inner wall 12 of the supplemental housing and in the partition 11 is a shaft 13 which extends into the main housing and has mounted on its inner end a beveled gear 14 which meshes with the beveled gear 5. The outer end of the shaft 65 extends beyond the outer wall of the supplemental housing and has rigidly secured thereto a ratchet wheel 16 with which cooperates a pawl 17 carried by a lever socket 18 pivotally mounted on the end of the shaft. The manipulation of this lever will rotate 70 the shaft 13 in the direction to impart lifting movement to the lifting element.

75 The downward movement of the lifting element is normally prevented by suitable controlling devices of such a character that 80 they will not interfere with the elevation of the lifting element but will normally prevent the downward movement thereof. This controlling device comprises means, however, for releasing the load to permit it to move 85 downwardly under its own weight, the lifting screw being of such a pitch that it will run downward under the weight of the normal load. In the present embodiment of the invention the controlling mechanism 90 comprises a worm gear 19 rotatably mounted on the shaft 13 and meshing with a worm 20 secured to a shaft 20^a which extends transversely to the shaft 13. The worm 20 is connected at its rear end with a brake shaft 95 21 to which is rigidly secured a brake member or drum 22. The connection between the worm and the brake shaft may be of any suitable character and as here shown a worm gear 120 is connected with the worm 20 and 100 meshes with a worm 121 on the brake shaft 21.

105 The worm gear 19 being loosely mounted on the shaft 13 will not interfere with the rotation of that shaft during the elevation of the load and a one-way clutch is interposed between the worm gear and the shaft to cause the worm gear to rotate with the

shaft when the latter is rotated in a reverse direction by the downward movement of the lifting element. In the present construction, this clutch comprises a ratchet wheel 23 rigidly secured to the shaft 13 adjacent to the worm gear 19, this gear being here shown as provided with a recess in its outer face so that the periphery thereof partially overhangs the ratchet wheel. Rigidly secured to the worm gear, partially within the recess therein, is a pawl carrier or frame which, as here shown, comprises an inner annular frame member or plate 24 which is rigidly secured to the web of the worm gear by means of a series of studs 25 and 26, each of which is provided with a collar 27 seated in a recess in the outer face of the annular plate 24 and has its inner end projecting through the web of the worm gear and upset or riveted to rigidly secure the same thereto. Each of the studs 25 and 26 project beyond the outer face of the annular plate 24 and these studs form supports, respectively, for pawls and springs. The inner member 24 of the pawl carrier has rigidly secured thereto and preferably formed integral therewith a series of abutments 28 which extend across the ratchet wheel and to the outer ends of which the outer member 29 of the pawl carrier is secured, this outer member also being in the form of an annular plate and being here shown as secured to the abutments by screws 30. The several abutments 28 are spaced short distances in the rear of the respective studs 26 and each abutment is provided in that edge adjacent to the corresponding stud with a curved recess 31, the surface of which conforms substantially with the arc of a circle described about the axis of the stud. Mounted on each stud 26 is a pawl 32 having its ends shaped to fit within the recess 31 of the adjacent abutment. The pawl is loosely mounted on the stud, the opening therethrough being of greater diameter than the diameter of the stud, so that the thrust on the pawl will be against the abutment and not against the stud. The studs 25 are arranged in the rear of the respective abutments 28 and between the same and the free ends of the succeeding pawls. Coiled about each of these studs 25 is a spring 33 having an end portion 34 projecting from one side thereof and engaging the rear edge of the adjacent abutment 28. The other end portion 35 of the spring projects rearwardly and engages the free end of the succeeding pawl to press the same against the ratchet wheel. Each spring is coiled loosely about its stud 25 so that when placed under tension the coils may contract, thus permitting the easy compression of the spring and avoiding the localizing of the strains. Such a construction permits the use of a strong spring but

provides the same with a large degree of resiliency and a corresponding ease of operation. Further, the arrangement enables the force to be applied to the pawl near the free end thereof where it will be most effectively utilized.

It will be apparent, therefore, that when the lifting element moves downward the clutch will connect the worm gear with the shaft 13 and cause this worm gear to rotate. The pitch of the teeth on the worm gear and worm 20 is such that the worm gear will drive the worm and movement will be transmitted from the worm shaft 21 to the brake member or drum 22. Cooperating with this brake member is a friction device which may be caused to engage the brake member to prevent or retard its rotation. Preferably this friction device is provided with parts which are movable toward and from one another to control the action of the friction device on the brake member. These movable parts may be arranged in any suitable relation to the friction device and, as here shown, are so arranged that their movement one toward the other will cause the friction device to operatively engage the brake member. The movable parts are acted upon by a yieldable device which tends normally to so move the parts as to cause the friction device to grip the brake member but which may be manually retracted to relieve the gripping action of the friction device to the desired extent. Associated with this yieldable device are means for positively holding the friction device in gripping engagement with the brake member and to thus lock the brake member against movement.

The controlling devices for the friction device may take various forms and may be arranged in various positions with relation one to the other. In that form of mechanism here illustrated the friction device consists of a single annular member or split ring 54, the split side of which is arranged at the forward side of the brake drum and is provided with forwardly extending lugs 55 the outer edges of which are preferably tapered. The friction member is provided at its rear side with a recess to receive a fixed stud or pin 56 which centers the same with relation to the brake member. Slidably mounted within the housing 10 is a slide block 57 which is here shown as mounted in a guideway 58 rigidly secured to the partition 11 and which has in its rear end a tapered recess 59 to receive the forward ends of the tapered parts or lugs 55 of the friction device. A spring acts on this slide block to press the same rearwardly and cause the friction device to normally grip the brake member. Preferably the slide block is provided with a forwardly extending stem or shank 60 about which is coiled

a spring 61 which is confined between the side wall of the housing and the slide block and tends to move that block rearwardly. The stem 60 has a reduced portion which extends through an opening in the side wall of the housing and this reduced portion is here shown as a separate rod 62 which is screw threaded into the stem 60 and provided on its outer end with a knob 63 by means of which the stem and slide block may be drawn outwardly against the action of the spring to release the friction device. A plunger 64 is screw threaded into the opening through which the rod 62 extends and is provided with a longitudinal bore in which that rod is slidably mounted. This plunger is provided with a knob or head 65 by means of which it may be rotated to cause the inner end thereof to be moved into contact with the end of the stem 60 and thus move the slide block into engagement with the parts 55 of the friction device and to positively hold the latter in operative engagement with the brake drum.

25 While I have shown and described certain embodiments of my invention I wish it to be understood that I do not desire to be limited to the details thereof as various modifications may occur to a person skilled in the art.

Having now fully described my invention, what I claim as new and desire to secure by Letters Patent, is:

1. In a lifting jack, the combination with a lifting element, means for actuating the same to lift the load, a rotatable brake member, means for causing said brake member to be rotated by the downward movement of said lifting element, and a friction device cooperating with said brake member to control the downward movement of said lifting element, of controlling mechanism comprising separately operable means to normally control the action of said friction device and to positively retain said friction device in contact with said brake member.

2. In a lifting jack, the combination with a lifting element, means for actuating the same to lift the load, a rotatable brake member, means for causing said brake member to be rotated by the downward movement of said lifting element, and a friction device cooperating with said brake member to control the downward movement of said lifting element, of controlling mechanism comprising manually operated means to normally control the action of said friction device, and a screw threaded member to lock said friction device in contact with said brake member.

3. In a lifting jack, the combination with a lifting element, means for actuating the same to lift the load, a rotatable brake member, means for causing said brake member to be rotated by the downward movement

of said lifting element, and a friction device cooperating with said brake member and comprising parts movable toward and from each other to control the contact between said friction device and said brake member, 70 of a single locking member movable into engagement with both of said parts to lock said friction device in contact with said brake member.

4. In a lifting jack, the combination with a lifting element, means for actuating the same to lift the load, a rotatable brake member, means for causing said brake member to be rotated by the downward movement of said lifting element, and a friction device 80 cooperating with said brake member and comprising parts movable toward and from each other to control the contact between said friction device and said brake member, of a single locking member movable into 85 wedging engagement with said parts to lock said friction device in contact with said brake member.

5. In a lifting jack, the combination with a lifting element, means for actuating the same to lift the load, a rotatable brake member, means for causing said brake member to be rotated by the downward movement of said lifting element, and a friction device 90 cooperating with said brake member and comprising parts movable toward and from each other to control the contact between said friction device and said brake member, of controlling mechanism comprising means to normally control the action of said friction device, and a screw acting on said parts to lock said friction device in contact with said brake member.

6. In a lifting jack, the combination with a lifting element, means for actuating the same to lift the load, a rotatable brake member, means for causing said brake member to be rotated by the downward movement of said lifting element, and a friction device 100 cooperating with said brake member and comprising parts movable toward and from each other to control the contact between said friction device and said brake member, said parts having contact surfaces converging one toward the other, of a locking member to engage said converging surfaces, and means for actuating said locking member and holding the same positively in engagement with said surfaces.

7. In a lifting jack, the combination with a lifting element, means for actuating the same to lift the load, a rotatable brake member, means for causing said brake member to be rotated by the downward movement of said lifting element, and a friction device 110 cooperating with said brake member to control the downward movement of said lifting element, of a mechanism to control the action of said friction device on said brake member comprising a spring to hold the fric- 115

tion device normally in contact with said brake member, manually operated means to release said brake member, and means other than said spring to retain said friction device in contact with said brake member.

8. In a lifting jack, the combination with a lifting element, means for actuating the same, to lift the load, a rotatable brake member, means for causing said brake member to be rotated by the downward movement of said lifting element, a friction device cooperating with said brake member to control the downward movement of said lifting element, a spring acting on said friction device to hold the same normally in contact with said brake member, and manually operated means for releasing said friction device from the action of said spring, of a locking device to positively retain said friction device in contact with said brake member.

9. In a lifting jack, the combination with a lifting element, means for actuating the same to lift the load, a rotatable brake member, means for causing said brake member to be rotated by the downward movement of said lifting element, and a friction device cooperating with said brake member and comprising parts movable toward and from each other to control the contact between said friction device and said brake member, of a spring acting on said friction device to hold the same normally in contact with said brake member a manually operated device to release said friction device from the action of said spring, and a screw operated device to engage said parts and retain said friction device in contact with said brake member.

10. In a lifting jack, the combination with a lifting element, means for actuating the same to lift the load, a rotatable brake member, means for causing said brake member to be rotated by the downward movement of said lifting element, a friction device comprising contact members to engage said brake member, and pivoted arms connected with said contact members to move the same into and out of engagement with said brake member, of a spring acting on said arms to hold said contact members normally in engagement with said brake member, means to release said arms from the action of said spring, a device to engage said arms and positively retain said contact members in engagement with said brake member.

11. In a lifting jack, the combination with a lifting element, means for actuating the same to lift the load, a rotatable brake member, means for causing said brake member to be rotated by the downward movement of said lifting element, and a friction device cooperating with said brake member and comprising parts movable toward and from each other to control the contact between said friction device and said brake member, a slide block having a recess provided with

converging walls to engage said parts, and a spring acting on said slide block to move the same toward said friction device.

12. In a lifting jack, the combination with a lifting element, means for actuating the same to lift the load, a rotatable brake member, means for causing said brake member to be rotated by the downward movement of said lifting element, and a friction device cooperating with said brake member and comprising parts movable toward and from each other to control the contact between said friction device and said brake member, of a slide block having a recess provided with converging walls to engage said parts, a spring acting on said slide block to move the same toward said friction device, and a screw acting on said slide block to hold the same positively in engagement with said parts of said friction device.

13. In a lifting jack, the combination with a lifting element, means for actuating the same to lift the load, a rotatable brake member, means for causing said brake member to be rotated by the downward movement of said lifting element, and a friction device having parts movable toward and from each other to control said brake member, of a slide block having a tapered recess in one end thereof to receive said parts of said friction device, a stem for said slide block, a spring acting on said slide block to move the same into engagement with said parts of said friction device, means for retracting said slide block against the action of said spring, and a screw threaded plunger movable into a position to engage said stem and hold said slide block in engagement with said parts of said friction device.

14. In a mechanism of the character described, the combination with a rotatable brake member, and a friction device to cooperate with said brake member, of a spring acting on said friction device to hold the same normally in engagement with said brake member, and a screw actuated member to positively retain said friction device in engagement with said brake member.

15. In a mechanism of the character described, the combination with a rotatable brake member, and a friction device to cooperate with said brake member, of controlling mechanism comprising manually controlled means to normally control the action of said friction device, and means operable independently of said manually controlled means to positively retain said friction device in engagement with said brake member.

16. In a mechanism of the character described, the combination with a rotatable brake member, and a friction device cooperating with said brake member and comprising parts movable toward and from each other to control the contact between said friction device and said brake member, of

controlling mechanism acting on said parts of said friction device and comprising means to normally control the action of said friction device and other means to lock said friction device in contact with said brake member.

17. In a mechanism of the character described, the combination with a rotatable brake member, and a friction device cooperating with said brake member and comprising parts movable toward and from each other to control the contact between said friction device and said brake member, of controlling mechanism comprising a device movable into wedging engagement with said parts, means to lock said device in engagement with said parts, and means operable independently of the last mentioned means to normally control the action of said friction device.

18. In a mechanism of the character described, the combination with a rotatable brake member and a friction device cooperating with said brake member and comprising parts movable toward and from each other to control the contact between said friction device and said brake member, said parts having contact surfaces converging one toward the other, of a locking member to engage said converging surfaces, and means for actuating said locking member and for holding the same in positive engagement with said surfaces.

19. In a mechanism of the character described, the combination with a rotatable brake member and a friction device cooperating with said brake member and comprising parts movable toward and from each other to control the contact between said friction device and said brake member, of a spring actuated device to hold said friction device normally in contact with said brake member, a manually operated device to move said spring actuated device against the action of its spring to release said brake member, and screw operated means to retain said friction device in contact with said brake member.

20. In a mechanism of the character described, the combination with a rotatable brake member and a friction device cooperating with said brake member and comprising parts movable toward and from each other to control the contact between said friction device and said brake member, of a controlling device acting on said movable parts of said friction device to cause the lat-

ter to engage said brake member, a spring acting on said controlling device to cause said friction device to be held normally in 60 engagement with said brake member, and other means acting on said controlling device to positively lock said friction device in engagement with said brake member.

21. In a mechanism of the character described, the combination with a rotatable brake member and a friction device cooperating with said brake member and comprising parts movable toward and from each other to control the contact between said 70 friction device and said brake member, of a slidible member having a recess to receive said parts of said friction device and engage the same with a wedging action, and a spring acting on said slidible member to cause the 75 same to move said parts one toward the other.

22. In a mechanism of the character described, the combination with a rotatable brake member and a friction device cooperating with said brake member and comprising parts movable toward and from each other to control the contact between said friction device and said brake member, of a slidible member having a recess to receive 80 said parts of said friction device and engage the same with a wedging action, a spring acting on said slidible member to cause the same to move said parts one toward the other, and a screw actuated device 85 acting on said slidible member to cause the same to positively hold said parts against movement relatively one to the other.

23. In a mechanism of the character described, the combination with a rotatable brake member and a friction device cooperating with said brake member and comprising parts movable toward and from each other to control the contact between said friction device and said brake member, of a 90 slide block having a tapered recess in one end thereof to receive said parts of said friction device, a stem for said slide block, a spring acting on said slide block to move the same into engagement with said parts 100 of said friction device, means for retracting said slide block against the action of said spring, and a screw threaded plunger movable into a position to engage said stem and hold said slide block in engagement with 105 said parts of said friction device.

In testimony whereof, I affix my signature hereto.

JAMES C. DAWLEY.
